UNITED STATES PATENT OFFICE.

GEORGE W. SLATER, OF PHILADELPHIA, PENNSYLVANIA.

HEATING OR VULCANIZING APPARATUS.

SPECIFICATION forming part of Letters Patent No. 606,364, dated June 28, 1898.

Application filed March 10, 1898. Serial No. 673,360. (No model.)

To all whom it may concern:

Be it known that I, GEORGE W. SLATER, a citizen of the United States, residing in the city and county of Philadelphia, State of Pennsylvania, have invented a new and useful Improvement in Heating or Vulcanizing Apparatus, which improvement is fully set forth in the following specification and accompanying drawings.

10 My invention consists of an improved construction of heating or vulcanizing apparatus which is especially applicable for vulcanizing pneumatic tires or mending other rubber substances, the apparatus being cheaply manufactured and the various parts thereof readily assembled.

15 It further consists of novel details of construction, all as will be hereinafter fully set forth, and particularly pointed out in the 20 claims.

Figure 1 represents a perspective view of a heating or vulcanizing apparatus embodying my invention. Fig. 2 represents a section on line *x x*, Fig. 1. Fig. 3 represents a perspective view of the lower part of the yoke or bail employed.

Similar letters of reference indicate corresponding parts in the figures.

Referring to the drawings, A designates a 30 heating or vulcanizing apparatus consisting of a lower member, burner, or base B, which may be provided with feet and has a chamber C within the same for the reception of the material D, which may be asbestos, mineral 35 wool, or other material, which latter is adapted to be saturated with the heating medium, which may be alcohol or other ignitable fluid.

E designates a plug in engagement with the bottom of the base D for the purpose of rendering the chamber C accessible or for the 40 purpose of enabling gas to be used as the heating medium.

F designates a cap adapted to be screwed or otherwise secured to the wick-tube F', said 45 cap serving as a closure for the opening G when the apparatus is not in use.

H designates a flue or chimney forming the combustion-chamber, which is supported upon the base B and is provided with the recesses 50 J for the admission of oxygen and to provide the necessary draft-passages for the support

of combustion, the lower portions or feet of said combustion-chamber being held in proper position relative to the base B by means of the upwardly-extending walls or flanges B^X. 55

K designates a bed which is supported on the upper portion of the combustion-chamber H and is provided with the lugs M, which project into said chamber, said bed having the concave portion L, above which is located the 60 follower or member N of the clamping device M', the latter consisting of the yoke Q, which has at its lower portion the lips R, which engage the lugs S, which latter are in the present instance oppositely located near the top 65 of the combustion-chamber H. The upper portion of the yoke Q has the thumb-screw T passing therethrough, the extremity of which is adapted to engage the member N, by means of which latter and the bed K the pneumatic 70 tire or other article N' of rubber or similar material can be rigidly held while being vulcanized, as will be hereinafter explained.

The top corners of the flue H are beveled or cut away in downward direction, so that 75 the recesses or passages D' exist between the chimney and the bed K, and providing, with the recesses J, for a draft through said flue and permitting the escape of the products of combustion therefrom, while, however, causing 80 said products to impinge the under side of said bed.

It will be noticed that while the lugs M prevent shifting or displacement of the bed K they serve to retard the escape of the products of combustion from the flue and so retain them sufficiently long against the bed as to highly heat the latter, after which they enter the uncovered corners of the flues and so escape. 90

The operation is as follows: The tire is placed in position (seen in Fig. 1) with the puncture against the bed K, and the member N is then screwed against the tire to the desired extent. The cap F having been removed and the burner ignited, it will be seen that the heat will be applied to the under side of the bed K, and after the tire has been vulcanized to the desired extent the same can be readily removed by loosening the screw 95 P, as is evident. 100

If desired, I may employ gas as the heat-

ing medium by removing the plug E and the material D and also the cap F, as is evident.

The upper faces of the lips R and under faces of the lugs S are curved, respectively, 5 in reverse direction, so as to interlock, and thus prevent the shifting or displacement of the yoke or bail Q from the chamber or flue H.

Having thus described my invention, what I claim as new, and desire to secure by Letters 10 Patent, is—

1. In a heating or vulcanizing apparatus, the combination of a base, a flue or combustion-chamber supported thereupon, a bed supported upon said combustion-chamber and 15 a clamping device, the latter consisting of a yoke having lips for engagement with lugs on said combustion-chamber, a member located above said bed, and a thumb-screw passing through said yoke and engaging said member.

2. A hollow base, a flue supported thereon, a bed mounted on said flue, a follower above the same, a screw carrying said follower and a yoke in which said screw is fitted, said flue having on its sides outwardly-turned lugs 25 and said yoke having on its under ends inwardly-turned lips, which latter are removably engaged with said lugs.

3. A hollow base, a flue supported thereon, a bed mounted on said flue, a follower above 30 the same, a screw carrying said follower and

a yoke in which said screw is fitted, said flue having on its sides outwardly-turned lugs and said yoke having on its under ends inwardly-turned lips, which latter are removably engaged with said lugs, said bed having 35 downwardly-projecting lugs which enter said flue.

4. In a heating and vulcanizing apparatus, a heater, a flue, a removable bed closing the top of said flue, a follower above said bed and 40 a device for clamping said bed and follower to said flue, said bed having lugs which enter said flue, and the corners of the latter being cut away, forming discharge-openings, whereby the products of combustion directed 45 against said bed are retarded by said lugs and discharged through said corner-openings.

5. In a device of the character stated, a flue with outwardly-projecting lugs on the sides thereof, a bed supported on said flue, a follower above said bed, a screw carrying said follower, and a yoke to which the said screw is fitted, said yoke having inturned lips which engage said lugs, the contiguous faces of said 50 lips and lugs being reversely curved.

GEORGE W. SLATER.
